Primary Examiner — R. Johnson(74) *Attorney, Agent, or Firm* — Innovation Law Office; Dennis S. Schell(57) **CLAIM**

The ornamental design for a synthesizer module as shown and described.

DESCRIPTION

FIG. 1 is a front perspective view of the synthesizer module; FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The broken lines shown in the drawings are for the purpose of illustrating portions of the article that form no part of the claimed design.
